UNITED STATES PATENT OFFICE.

PONTUS OSTENBERG, OF SAN JOSE, CALIFORNIA.

PUMP MECHANISM.

Application filed October 12, 1920. Serial No. 416,428.

To all whom it may concern:

Be it known that I, PONTUS OSTENBERG, a citizen of the United States, and a resident of San Jose, in the county of Santa Clara and State of California, have invented certain new and useful Improvements in Pump Mechanisms, of which the following is a specification.

My invention relates particularly to the driving mechanism of pumps.

It is customary to build up the driving shaft for a deep well centrifugal pump by joining several lengths of shafting together by means of threaded couplings. The shaft ends and couplings are threaded in such a manner that in operating the pump in the right direction the tendency is to screw the parts up more tightly. If, however, the belt is inadvertently twisted in the wrong direction when being placed upon the pulley driving the shaft, and the shaft is therefore driven in the reverse direction to that for which it was designed, any one of these couplings may be unscrewed. The accidental unscrewing of a coupling in this manner, especially if it should occur several hundred feet below the surface of the ground, as it sometimes does, occasions considerable expense of time and money in rejoining the several parts as well as loss of use of the pump during the lifting of the pump, the joining of the parts and the replacing of the pump in the well.

It is the object of my invention to provide an automatically operating means whereby the pump shaft may be revolved freely in the right direction but effectively held against rotation in the reverse direction. It is another object of my invention to provide a new and novel means of circulating oil through the ball bearings in the pump head.

In the drawing:—

Figure 1 is an illustration of a pump head embodying my invention, one-half being in elevation and one-half in section.

Figure 2 is a sectional view on line 2—2 of Figure 1.

Figure 3 is an illustration of another embodiment of my invention.

Figure 4 is a plan view of another embodiment of my invention.

Figure 5 is a side elevation of the movable member shown in Figure 4.

Referring more particularly to the draw-

ing, 1 is the body of the pump head, 2 the discharge casing connected thereto, 3 the discharge pipe from said head, 4 the ball bearings in the head covered by cap 5, 6 the driving shaft in bearing 4, and 7 the driving pulley for shaft 6.

The shaft 6 is shown with a coupling at 8 into which opposing ends of shaft sections are screwed as at 9 and 10. At 11 is shown a flange extending inwardly from head 1 just below bearings 4 as shown. At 12 is shown an oil receptacle mounted on shaft 6 to revolve therewith and having a top flange 13 extending inwardly a distance as shown. A tube is shown at 14 extending from a point adjacent the bottom and outer wall of receptacle 12 upwardly and over flange 13 to a point in the head 1 to which it is secured. A conduit 15 is formed in head 1 extending from tube 14 to a point 16 where it discharges into ball bearings 4.

In the outer surface of head 1 are formed several stops as 17 and a dog 18 is shown mounted upon a pin 19 set in lugs 20 formed on pulley 7, the dog 18 being positioned to normally engage a stop 17 as shown when the pulley is at rest. This engagement is effected by a spring 21 on the outer edge of dog 18 and engaging the said pulley 7.

When the shaft 6 is revolved the oil in receptacle 12 is thrown outwardly by centrifugal force and forced to travel upwardly through tube 14 and conduit 15, and is discharged at 16 on to the ball bearings 4. When the oil works down to flange 11 it passes over the edge thereof into receptacle 12, to be again thrown outwardly and forced into tube 14.

When pulley 7 starts to revolve dog 18 travels over the surface of head 1, but as the speed of the pulley increases, the centrifugal force generated acts upon dog 18 and throws it outwardly to an inoperative position as 22 against the tension of spring 21. When the pulley 7 again slows down to a stop the dog 18 assumes the normal position shown. With this device in position it is impossible to reverse the direction of movement of shaft 6 for more than a quarter of a turn as the dog will automatically engage a stop 17 and prevent its further revolution in that direction, and a quarter of a turn in the reverse direction would of course be insufficient to unscrew the parts.

8—9—10. Of course one or any number of stops may be provided to secure the results desired.

In the embodiment shown in Figure 3 the action is similar to that described but the dog is formed with an inwardly extending arm 23 and an upwardly extending weighted arm 23^a. The centrifugal force acting upon arm 23^a throws it outwardly and removes arm 23 to an inoperative position.

In Figures 4 and 5 I show an outwardly extending flange 24 on head 1, the stop 17 being arranged thereon. On pin 25 on pulley 7 is pivotally mounted a dog 26 formed of thin flat metal normally inclined downwardly as shown in Figure 5. On the under side of dog 26 is a rib 27 normally engaging flange 24 and a stop 17 thereby preventing the reverse movement of pulley 7 and shaft 6. The speed of the rotating pulley 7, however, imparts a certain buoyancy to dog 26, the air engaging its under side and causing it to assume a substantially horizontal position as shown at 28. As the air pressure is reduced by the stopping of pulley 7 the dog automatically

drops back to a normal position in operative relation to stop 17.

It is to be understood of course, that this invention may be adapted for use in connection with any pulley and shaft arrangement where the reverse rotation of the shaft must be avoided, and that changes in form, construction and method of operation may be made within the scope of the appended claim.

It is also to be understood that changes in form and construction of the oiling system described may be made within the scope of the appended claim.

I claim:

In combination, a pump head, a shaft revolvably mounted therein, a pulley on said shaft, a stop on said head, and a dog pivotally mounted on said pulley and carrying an inwardly extending arm normally positioned to engage said stop and a vertically extending arm movable outwardly about its pivotal point by the revolution of said pulley whereby to raise said first mentioned arm to an inoperative position.

PONTUS OSTENBERG.
